[57] CLAIM

The ornamental design for a container for food such as tacos, as shown and described.

DESCRIPTION

FIG. 1 is a front elevational view of a container for food such as tacos showing my new design;

FIG. 2 is a top plan view thereof;

FIG. 3 is a side elevational view thereof;

FIG. 4 is a bottom plan view thereof;

FIG. 5 is a rear elevational view thereof; and

FIG. 6 is a cross sectional view taken through FIG. 2 along line 6—6 illustrating the container in a partially opened position.

*Fig. 2.**Fig. 3.**Fig. 1.**Fig. 4.**Fig. 6.**Fig. 5.*
